TABLE-LOCK.

1,185,527.

Specification of Letters Patent. Patented May 30, 1916.

Application filed October 3, 1914. Serial No. 864,924.

To all whom it may concern:

Be it known that I, WILLIAM H. NORTHELL, a citizen of the United States, residing at Evansville, in the county of Vanderburgh and State of Indiana, have invented a new and useful Table-Lock, of which the following is a specification.

This invention has reference to locks for extension tables, and its object is to provide a lock which may be applied to extension tables whether supplied with wooden or metal slides, whereby the table may be locked in the fully extended position with all the leaves in, or may be locked in the partially extended position with some of the leaves in, or in the fully closed position with all the leaves out.

In accordance with the present invention there is provided a lock structure readily attachable to an extension table at a point midway of the width thereof, and so arranged that it will adapt itself to different numbers and widths of table leaves and to some variations in the widths of the leaves, whereby the table will always lock in the desired position with the parts held firmly together against separation.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings: Figure 1 is a top plan view of the pedestal portion of an extension table of the pedestal type with the invention applied and the table top shown in the closed position in dotted lines, the fastening devices securing the table top to the pedestal members and a portion of the lock to the table top being shown in cross-section. Fig. 2 is a vertical section of an extension table of the pedestal type along the line of the applied lock but showing the latter in elevation. Fig. 3 is a plan view of the lock on a larger scale than the showing of Fig. 1. Fig. 4 is a longitudinal central vertical section of the lock shown in Fig. 3. Fig. 5

is a section on the line 5—5 of Fig. 4, but drawn on a larger scale. Fig. 6 is a section on the line 6—6 of Fig. 3.

Referring to the drawings there is shown a table comprising top members 1, 2, provided with slides 3 in turn supported by cross strips 4 carried by a pedestal 5 and united at their outer ends by intermediate connecting strips 6. These features are all present in certain forms of pedestal tables, and especially those with round or circular tops where the top members may be drawn away one from the other by a force applied to either, the slides 3 being of an interacting character to bring such a result about. The present invention, however, is not limited to such particular type of extension table, but is applicable to other types of extension tables, whether supported upon a central pedestal or upon a suitable number of legs.

The lock comprises two elongated bars 7, 8, the bar 8 being somewhat shorter than the bar 7 and attached to the latter in longitudinally slidable relation thereto by headed studs 9 on the bar 8 projecting through slots 10 in the bar 7, the two bars being slightly spaced apart by washers 11 on the studs 9 and located between the two bars. The studs 9 have heads 12 overriding the bar 7 along the edges of each slot 10. These slots are angle slots and have a portion 13 parallel with and adjacent to one edge of the bar 7 and another portion 14 extending from one end of what may be termed the straight portion 13 at an angle thereto toward the other side of the bar 7. While the bars 7 and 8 may be of any appropriate shape they are preferably flat and relatively narrow. One slot 10 is located near one end of the bar 7 and the other slot 10 is located nearer the middle of the bar than toward the other end thereof. Pivotaly mounted on the bar 7 near the end remote from the first-named slot 10 is a rock head 15 carried by a pivot 16 in turn carried by the bar 7. This rock head 15 has an offset handle portion 17 spaced away from the bar 7 on the same side thereof as the bar 8 and in the main parallel with the bar 7. Pivotaly connected to the head 15 to one side of the pivot 16 is one end of a link 18 the other end being connected to the corresponding end of the bar 8 by a pivot 19. The head 15 is formed on opposite sides with outstanding projections 20, 21 in

the path of which is a stud 22 projecting 110

from the corresponding face of the bar 7. When the head 15 is rocked by a suitable manipulation of the handle 17 it has a range of movement corresponding to the distance 5 between the projections 20 and 21 as measured by an arc struck about the pivot 16 and the rocking movement of the head 15 causes through the link 18 a reciprocatory movement of the bar 8, which movement is translated into a lateral shift by the inclined or angle portions 14 of the slots 10, while during a certain portion of the longitudinal movement of the bar 8 its path of movement is parallel with the longitudinal center line 10 of the bar 7 due to the portions 13 of the slots 10 which are themselves parallel with such center line. There is also provided a plate 23 designed to be made fast to any suitable portion of the slide supporting part 15 of the table, and in the drawings this plate 23 is shown as secured to one of the connecting strips 6. Along one edge of the plate 23 there is formed an upstanding flange 24 with two passages 25, 26 therethrough. The 20 passage 25 is traversed by the bars 7 and 8 and is long enough in the direction of the length of the flange 24 to permit movements of the two bars simultaneously through the slot when the bar 8 is in the position of 25 greatest sidewise projection with relation to the bar 7.

Fast to the plate 23 near that end thereof corresponding to the position of the passage 26 is a stud 27 on which is pivoted one end 30 of a pawl 28 provided with an extension 29 at the end thereof remote from the pivot stud 27, this extension 29 being of sufficient length to project through the passage 26. At one side of the pawl 28 there is formed 35 an engaging nose 30 and along the corresponding edge of the bar 8 are a suitable number of series of notches forming teeth 31 between them. The teeth 31 are arranged in a suitable number of longitudinally disposed groups spaced apart so that the centers of the groups are separated by about the width of average table leaves, while the length of each group is sufficient to include 40 variation in the widths of table leaves within the limits usually employed. The stud 27 carries an intermediate coil of a spring 32 having two branches 33, 34. The branch 33 of the spring is of sufficient length to extend 45 through the passage 26 and engage one end thereof, while the branch 34 bears against the rear edge of the nose 30, which latter upstands from the pawl 28 sufficiently to be engaged by the branch 34 of the spring, and also to engage the teeth 31 along the corresponding edge of the bar 8. The teeth 31 and pawl nose 30 are all inclined in one direction, so that the bar 8 may be moved lengthwise in one direction without being arrested in such movement by the engagement 50 of the nose 30 with any one of the teeth

31, for the teeth then ride idly under the nose 30 of the pawl, the latter yielding to such movement. The spring 32, however, tends constantly to hold the nose 30 in the path of the teeth and when the attempt is 55 made to move the bar 8 in the opposite direction to that just considered the nose 30 locks behind some one of the teeth 31, and so effectively prevents any movement of the bar 8 in the reverse direction to that first 60 considered. The pawl 28, however, will move only a certain definite distance toward the bar 8 under the action of the spring 32 before the extension 29 arrests further movement in such direction by engagement with 65 the corresponding end of the passage 26, but the pawl may rock in the contrary direction against the normal tendency of the branch 34 of the spring 32, since the passage 26 is of sufficient length for the purpose. When the 70 studs 9 are in the longitudinal portions of the slots 10 the pawl 30 is in the path of the teeth 31, but when the studs 9 are in the inclined portions 14 of the slots 10 toward the closed ends of these inclined portions, 75 then the pawl nose 30 is no longer in the path of the teeth 31, since its movement theretoward is arrested by the extension 29 and the pawl 28 becomes inactive to the bars 7 and 8.

That end of the bar 7 carrying the head 15 is prolonged beyond said head and terminates in an angle abutment 35. Between the head 15 and the angle abutment 35 the bar 7 bears against one face of a plate 36 80 having at one end an angle flange 37 and at the other end an oppositely directed angle flange 38. Extending longitudinally of the plate 36 for the greater portion of its length and into the flange 37 is a slot 39 midway 85 between the sides of the plate. Threaded through the flange 38 midway of its length is an adjusting screw 40 bearing at the inner end against a headed follower 41 entering one end of a helical spring 42, while the 90 other end of this spring bears against the abutment 35 at the corresponding end of the bar 7, this abutment carrying a pin 43 entering the corresponding end of the spring 42.

The plate 36 adjacent to the end provided 95 with the flange 38 carries a stud 44 projecting through a longitudinally extended slot 45 in the corresponding portion of the bar 7, and the stud 44 is headed, as shown at 46, against the other face of the bar 7 from that 100 engaging the plate 36, so that the bar may have longitudinal movement with respect to the plate for a distance limited by the length of the slot. The plate 36 is mounted on a block 47 which is suitably channeled as 105 shown at 48 for the reception of the spring 42, and this block has side wings 49 for screws or other fastening devices 50 securing the block 47 to the under side of the section 110 1 of the table top. The block 47 serves as a 115

spacing member permitting the bars 7 and 8 to move on the plate 23 made fast to the strip 6, so that the plates 23 and 36 are close to and on opposite sides of the bars 5 7 and 8. The opening 25 is only long enough where traversed by the bar 7 to permit this bar to move freely therethrough without any material side movement, and the passage 25 has a side extension 25^a at the end toward 10 the passage 26 to admit of the movement of the toothed edge of the bar 8 therethrough when this bar is laterally displaced with respect to the bar 7.

When the handle 17 is moved to one side 15 of the longitudinal center line of the bar 7 so that the extension 20 is brought into engagement with the pin or stud 22, the bar 8 is moved along the bar 7 to an extent causing the studs 9 to enter and move along the inclined extensions 14 of the slots 10, and then 20 the toothed edge of the bar 8 is caused to approach the corresponding edge of the bar 7 until nearly or quite coincident therewith and at any rate well out of the path of the 25 nose 30 of the pawl 28. Under these circumstances there is no impediment to the movement of the table top sections 1 and 2 toward and from each other to any desired extent, either for the extension of the table 30 or the retraction thereof. Let it be assumed that the table top is to be extended and leaves are to be placed therein. This is permitted by the movement of the lock handle 17 to the position just described, so that the 35 pawl 28 is inactive to the teeth 31. The table leaves are inserted and the table top sections are pushed together until the spaces between the leaves are reduced. Now the handle 17 is moved toward a position of 40 alignment with the bar 7, thus causing the studs 9 to travel in the inclined portions 14 of the slots 10, and this brings about a lateral and forward movement of the bar 8 so that some one of the teeth 37 engages the 45 nose 30. This occurs about the time that the studs 9 have reached the longitudinal portions 13 of the slots 10 and the handle 17 is approaching, although not quite yet in the central position. The remaining movement 50 of the handle to the central position causes a movement of the bar 8 lengthwise of the bar 7 tending to take up all spaces which may have existed between the table leaves, while a continued swing of the handle 17 to 55 the opposite side of the bar 7 until the abutment or extension 21 has reached the pin 22 tends to clamp the leaves tightly in place and in this position the link 18 is thrown beyond the center line of the bar 8 slightly 60 to the other side thereof from that first assumed, whereby no force tending to pull the bar 8 backwardly will swing the handle 17 in the reverse direction, but all forces then exerted upon the bar 8 tend to lock the 65 head 15 firmly in the last-named position.

The movement of the handle 17 from the fully unlocked position until a tooth 31 engages the nose 30 represents about the movement of the studs 9 along the inclined portion 14 of the slots 10, and the handle has 70 made about one-third of its full movement to the fully locked position. A continued movement of the handle 17 toward the fully locked position results in a longitudinal movement of the bar 7, since the bar 8 is 75 then locked against movement with respect to the pedestal of the table by the engagement of the pawl nose 30 with a tooth of the bar 8. The bar 7, however, is fast to one of the table top sections by way of the 80 plate 36, wherefore the table top sections are drawn together taking up all separation of the table top sections and of the leaves which may at the time be present, and this continues until the table top sections and 85 the leaves are brought into firm engagement. Under some circumstances this firm binding engagement may be accomplished only by practically the full movement of the handle 17 to the fully locked position with the projection 90 21 in engagement with the stud or pin 22. Under other circumstances the table top sections and the leaves or the table top sections without the leaves come into full engagement before the handle 17 has 95 reached the fully locked position. Under these circumstances the plate 36 is stopped in its movement, but the bar 7 may still move a limited distance lengthwise of the plate 36 because of the yielding of the 100 spring 42, and, therefore, the movement of the handle 17 may be continued to the fully locked position, being there firmly held by the out-of-line position of the link 18 on that side of the longitudinal center line of 105 the bar 7 and pivot 16 occupied by the stop pin or stud 22.

The structure constitutes a firm lock holding the parts of the table together against accidental separation, while the lock will 110 not spontaneously move out of locking position but must be manipulated purposely. The locking structure is adaptable to different types of extension tables irrespective of the character of the slides, whether wood or metal, or of the means whereby the table top sections may be made to move simultaneously in opposite directions. Moreover, the lock has an ample range of adjustment 115 to accommodate tables of different sizes and 120 widths of leaves.

What is claimed is:—

1. A lock structure for extension tables, comprising two connected elongated members movable along and also laterally one 125 with respect to the other, means in the path of one of the members when in laterally projected relation to the other for locking it to a member of the extension table, means for securing the other one of the two con- 130

- connected members to another member of the extension table, and means for imparting combined longitudinal and lateral movements to one of the two members, at will.
- 5 2. A lock structure for extension tables, comprising two connected elongated members movable along and laterally one with respect to the other, means in the path of one of the members when in laterally projected relation to the other for locking it to a member of the extension table, means for securing the other one of the two connected members to another member of the extension table and including an elastic connection yieldable to further movement of the said other one of the two connected members after the table sections have been brought into unyielding engagement, and means for imparting combined longitudinal and lateral movements to one of the two connected members, at will.
- 10 3. A table lock for extension tables comprising two elongated bars with one connected to the other for relative movement with respect thereto both longitudinally and laterally thereof, an operating member for imparting a movement to one bar with relation to the other, said first-named bar having a series of teeth produced on the edge thereof, a pawl member for engaging the teeth, a support for the pawl member for mounting the latter upon a relatively fixed part of the table, and another member connected to the second-named bar for securing it to one of the table top sections.
- 15 4. A table lock for extension tables, comprising two elongated bars with one connected to the other for relative movement with respect thereto both longitudinally and laterally thereof, an operating member for imparting a movement to one bar with relation to the other, said first-named bar having a series of teeth produced on the edge thereof, a pawl member for engaging the teeth, a support for the pawl member for mounting the latter upon a relatively fixed part of the table, and another member connected to the second-named bar for securing it to one of the table top sections, said last-named member and the second-named bar having elastically yieldable connections for transmitting longitudinal movement of the second-named bar with respect to the last-named member.
- 20 5. A lock for extension tables comprising an elongated flat bar with slots therein each having a portion of its length parallel with the longitudinal center line of the bar and the remaining portion extending across the bar at an obtuse angle to the first-named portion of the slot, another elongated flat bar having guiding connections extending through the slots, a supporting plate with an upturned edge provided with a passage for the joined bars and through which the

joined bars are longitudinally movable, a pawl mounted on the plate and provided with a nose in operative relation to one edge of the second-named bar, said edge having teeth thereon and the plate and pawl having coacting stop means for limiting movement of the pawl toward the toothed edge of the second-named bar, a handle member pivotally connected to the first-named bar, a link connecting the handle member to the second-named bar to one side of the pivot of said handle member, stop means on the handle member and first-named bar for limiting the movement of the handle member about the pivot, and means for connecting the first-named bar to one of the table top sections.

6. A lock for extension tables comprising an elongated flat bar with slots therein each having a portion of its length parallel with the longitudinal center line of the bar and the remaining portion extending across the bar at an obtuse angle to the first-named portion of the slot, another elongated flat bar having guiding connections extending through the slots, a supporting plate with an upturned edge provided with a passage for the joined bars and through which the joined bars are longitudinally movable, a pawl mounted on the plate and provided with a nose in operative relation to one edge of the second-named bar, said edge having teeth thereon and the plate and pawl having coacting stop means for limiting movement of the pawl toward the toothed edge of the second-named bar, a handle member pivotally connected to the first-named bar, a link connecting the handle member to the second-named bar to one side of the pivot of said handle member, stop means on the handle member and first-named bar for limiting the movement of the handle member about the pivot, and means for connecting the first-named bar to one of the table top sections, said last-named means comprising a plate with a slidable connection between the plate and first-named bar, and a spring interposed between the plate and first-named bar for yielding movement of the bar lengthwise thereof with respect to the plate.

7. A lock for extension tables, comprising an elongated flat bar with angle slots therein, another elongated angle bar having one edge provided with teeth and also provided with engaging connections with the first-named bar traversing the slots therein and guided thereby, a rockable head provided with a handle and pivotally connected to the first-named bar with the head and bar having co-acting stop means for limiting the extent of rocking of the head, a link connection between the second-named bar and the rockable head to one side of the pivot of the latter, a plate adapted to be

connected to a fixed portion of the table, said plate having an angle edge with adjacent passages therethrough, the two joined bars traversing one passage, a pawl pivotally mounted on the plate and provided with a spring urging the pawl toward the toothed edge of the second bar and having a portion extending through the second-named passage in the plate to limit movement of the pawl under the action of the spring toward the toothed edge of the second-named bar, another plate connected to the first-named bar and adapted in turn to be connected to one of the table top sections, 10 the second-named plate and the first-named bar being connected for limited relative longitudinal movement of the plate and bar, and a spring interposed between the plate and bar and tending to maintain the bar at one limit of its movement with respect to 15 the plate, said bar having one end at an angle to form an abutment for the spring, and the plate having one edge provided with an up-turned flange and an adjusting screw carried thereby for varying the tension of 20 the spring.

8. A lock for extension tables, comprising an elongated flat bar with angle slots therein, another elongated angle bar having one edge provided with teeth and also provided with engaging connections with the first-named bar traversing the slots therein and guided thereby, a rockable head provided with a handle and pivotally connected to the first-named bar with the head and bar having co-acting stop means for limiting the extent of rocking of the head, a link connection between the second-named bar and the rockable head to one side of the 30 pivot of the latter, a plate adapted to be connected to a fixed portion of the table, said plate having an angle edge with adjacent passages therethrough, the two joined bars traversing one passage, a pawl pivotally mounted on the plate and provided with a spring urging the pawl toward the toothed edge of the second bar and having a portion extending through the second-named passage in the plate to limit movement of the pawl under the action of the 40 spring toward the toothed edge of the second-named bar, another plate connected to

the first-named bar and adapted in turn to be connected to one of the table top sections, the second-named plate and the first-named bar being connected for limited relative longitudinal movement of the plate and bar, and a spring interposed between the plate and bar and tending to maintain the bar at one limit of its movement with respect to 50 the plate, said bar having one end at an angle to form an abutment for the spring, and the plate having one edge provided with an up-turned flange and an adjusting screw carried thereby for varying the tension of 55 the spring.

9. A lock for extension tables, comprising two elongated members relatively movable one on the other, an elastically yieldable means for connecting one member with 60 one section of the table top, one-way latch means for connecting the other member to a fixed portion of the table, and means for imparting relative movements of the two members lengthwise and laterally of each 65 other for the engagement and disengagement of the latch means.

10. A lock for extension tables, comprising two members, one mounted on and at all times connected to the other member, 70 means carried by the connected members for moving one of the two members with relation to the other, latch means for connecting one member to a portion of the extension table, and elastically yieldable 75 means for connecting the other member to another portion of the extension table, whereby the lock will elastically yield to further relative movement of said members after the table sections are brought into unyielding engagement.

In testimony, that I claim the foregoing as my own, I have hereto affixed my signature in the presence of two witnesses.

WILLIAM H. NORTHALL.
